ATTACHMENT FOR SEWING MACHINES

Filed Oct. 6, 1928

UNITED STATES PATENT OFFICE

CLARA MABEL SMITH, OF BROCKTON, MASSACHUSETTS

ATTACHMENT FOR SEWING MACHINES

Application filed October 6, 1928. Serial No. 310,814.

This invention relates to an attachment for sewing machines and it is an object of the invention to provide a device of this kind to facilitate the cording of an article and more especially when said article is of a pointed type.

The invention consists in the details of construction and in the combination and arrangement of the several parts of my improved attachment for sewing machines whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:

Figure 1 is a view in top plan of my improved attachment in applied position, the associated portion of the sewing machine plate and article being worked being shown in fragment;

Figure 2 is a view in side elevation of my improved attachment as herein disclosed, the associated work being diagrammatically associated therewith;

Figure 3 is a fragmentary view partly in section and partly in elevation illustrating the head of the sewing machine and the association of the needle with the cord being applied;

Figure 4 is a view partly in elevation and partly in transverse section of the attachment as herein disclosed and at that end portion of the attachment engaged with a plate of the sewing machine;

Figure 5 is a fragmentary view in bottom plan of the end portion of one of the arms of the attachment and the plate to which it is attached.

As disclosed in the accompanying drawing, P denotes a conventional plate of a sewing machine upon which in advance of the head H of the sewing machine proper is adapted to be positioned the plate 1 of my improved attachment. This plate 1 at approximately

its central portion has disposed therethrough a headed screw shank 2 which also engages a bar 3 which, when the attachment is in applied position, is adapted to have requisite contact from below with the plate P to hold the plate 1 in desired working position.

This plate 1 when applied is disposed over a suitable opening in the plate P used in connection with all conventional types of sewing machines and which is normally closed by a slide plate. It is to be understood that such slide plate is removed before the plate 1 is applied.

Underlying the plate 1 is a free end portion of an elongated arm 5, said end portion of the arm 5 being provided with a longitudinally disposed slot 6 of desired length and through which are directed the holding screws 7 in threaded engagement from below with the plate 1. The slot 6 is made relatively long so that the elongated arm 5 may be adjusted as desired relative to the plate 1 and the adjustment of this arm 5 will adjust the returned arm 9 disposed above the plate 1. The arm 5 is relatively long and formed of metal and its outer end is continued by an elongated returned arm 9 of a length to extend over the upper surface of the plate 1 and terminate a desired distance inwardly thereof when the attachment is in applied position as particularly illustrated in Figures 1 and 2 of the drawing.

This upper arm 9 has one marginal portion disposed inwardly on a predetermined incline, that is, one edge portion of the arm 9 converges toward the opposite edge so as to provide a relatively restricted end. The free extremity of the arm 9 is continued by a small angularly disposed eye 10 through which the cord C is threaded, said cord being also freely disposed through the guide eyes 11 carried by the arm 9 and projecting beyond the straight side edge thereof.

My improved attachment is especially designed for use in properly applying cord to an article, and when in use it is of particular importance that the head H be provided with a relatively small roll feed 12 which runs on a lower feed roll (not shown) as by such use it is possible to get up into the cen-

ter of the article better than with a large roll feed or a flat feed.

When the attachment is applied the eye 10 thereof is positioned closely adjacent to but slightly in advance of the needle N and said eye 10 and the adjacent portion of the arm 9 are disposed between the overlying laminations 14 and 15 and at a point closely adjacent to the initial stitching 16 for connecting such laminations. As clearly indicated in Figure 1, the cord C is employed to produce and maintain the desired embossing effect which materially increases the esthetic value of the article. Through the provision of the elongated slot 6, the eye 10 can be adjusted to the desired position relative to the needle and this adjustment can be effected on either side of the needle. Through the provision also of the clamping member 3 which is held in clamping position, the cover plate 1 can be adjusted by tightening or loosening this plate and then sliding the plate 1 to the desired position carrying with the plate the eye member 10 secured to the arm 9.

From the foregoing description it is thought to be obvious that an attachment for a sewing machine constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

A corder attachment for a sewing machine comprising a plate adapted to loosely and slidably engage the machine, means for clamping the plate in adjusted position on the machine, a cording member, said cording member having one end thereof longitudinally slotted and positioned beneath said plate whereby to prevent interference with the passage of material over the plate, and means for securing said cording member in adjusted position on said plate, said securing means extending through said slotted end of said member.

In testimony whereof I hereunto affix my signature.

CLARA MABEL SMITH.
